UNITED STATES PATENT OFFICE.

LELAND J. STACY, OF CALDWELL, NEW JERSEY, ASSIGNOR TO WESTERN ELECTRIC COMPANY, INCORPORATED, OF NEW YORK, N. Y., A CORPORATION OF NEW YORK.

TESTING DEVICE.

Application filed September 17, 1924. Serial No. 738,204.

To all whom it may concern:

Be it known that I, LELAND J. STACY, a citizen of the United States of America, residing at Caldwell, in the county of Essex, 5 State of New Jersey, have invented certain new and useful Improvements in Testing Devices, of which the following is a full, clear, concise, and exact description.

This invention relates to a method and apparatus for testing the operating characteristics of relays; more particularly, to the testing of ringing trip relays in telephone systems.

It is well known in the art that the ringing trip relays in ordinary telephone systems must function under rather severe conditions. Such relays must not operate when ringing current is applied to the line to ring a subscriber's bell but must operate as soon 10 as the called subscriber removes his receiver from the switchhook, at which time the bell and condenser are shunted by the transmitter and induction coil. As the electrical characteristics of the lines leading to subscribers' stations vary to a large degree, due 15 principally to the varying lengths thereof, and the electrical characteristics of the apparatus at the substations do not always remain constant due to the different type of 20 apparatus employed, it is readily seen that the ringing trip relays must function within very narrow limits. The operating characteristics of a ringing trip relay depend, 25 also, to a considerable extent on the point 30 of the wave of the ringing current at which the circuit for the relay is closed. In practice, it has been found that these relays may, in some instances, operate through as high 35 as a 50% higher resistance when the circuit 40 is closed at the zero point than when it is closed at the peak of a wave, and, as the ringing key may be closed at any point of the wave, it is apparent that the operating 45 limits are, thereby, further reduced.

It is an object of the invention to provide an arrangement whereby the operating characteristics of such ringing trip relays may readily be tested under conditions simulating the most severe conditions 50 encountered thereby in service.

Another object is the provision of means in a testing arrangement of this sort for indicating the operating characteristics of a

relay under test in a convenient and accurate manner without the use of elaborate and costly precision instruments.

Another object of the invention is the provision of a testing equipment of this type in a convenient unit, so that tests may be performed on the ringing trip relays as 60 actually installed and functioning in telephone exchanges and without disturbance to the telephone system as a whole.

Another object of this invention is the provision of a testing equipment for telephone circuit in which any of the standard type of varying current sources are employed.

To attain these objects, in accordance with one feature of the invention, a circuit arrangement has been provided, whereby the terminals of a ringing trip relay to be tested may be connected to the testing unit and whereby upon the manipulation of keys in this unit the relay is subjected to the full 70 potential from the ringing source when the current therefrom has reached the peak of a wave.

Another feature of the invention is the provision of means whereby the operating 80 and non-operating limits for the ringing trip relay are simulated in the testing unit by means of non-inductive resistances, and applicable through the operation of keys.

Another feature resides in the provision 85 of a signal in the testing unit for indicating the characteristics of a relay under test.

Another feature is the provision in this testing unit of certain standard testing 90 conditions to which relays under test may be adjusted to respond.

The invention has been illustrated in the accompanying drawings, in which Fig. 1 represents a circuit embodying the arrangement in accordance with this invention. This figure also shows a portion of an ordinary manual cord circuit including a ringing relay and a portion of a subscriber's station, while Fig. 2 illustrates the plug 95 ending portion of an automatic to manual machine switching system including a ringing relay that may be subject to test by an arrangement of the invention as shown in Fig. 1.

In order to more clearly show the actual

conditions under which the ringing relay will function, the operation of the relay in the manual telephone system shown in Fig. 1 may be briefly outlined as follows:

- 5 When the operator in calling the subscriber at a substation as 6 inserts her plug 7 in jack 8, a circuit is established as follows: battery winding of relay 9, armature and back contact of relay 10, armature and
10 back contact of ringing trip relay 5, sleeve contacts of plug 7 and jack 8 to ground. Relay 9 in operating now applies ringing current to the subscriber's bell over a circuit as follows: alternating current ringing
15 source 11, winding of relay 5, lower armature and front contact of relay 9, ring contacts of plug 7 and jack 8 to the subscriber's bell at the telephone set 6, tip contacts of jack 8 and plug 7, upper armature and front
20 contact of relay 9 to ground. Under these conditions the ringing trip relay 5 will not operate due principally to the high impedance of the bell and condenser when the subscriber, in responding to the call by removing the receiver from the switchhook, shunts the bell this ringing trip relay 5 is operated. In operating, relay 5 opens the shunt circuit for relay 10 at its armature and back contact. Relay 10 is, therefore,
25 operated in series with relay 9 and in operating shunts the winding of relay 9 to battery 16, causing relay 9 to release and thus remove the ringing current from the line whereupon relay 5 releases.
- 30 It is readily seen, therefore, that relay 5 must not operate in a circuit containing the bell and condenser, but operate when these are shunted and therefore function within very close limits. These limits are further
35 restricted as the electrical conditions of this circuit vary to an appreciable extent due principally to the varying resistance of the subscribers' lines the lengths of which cannot be uniform as well as to the varying electrical conditions of the substation apparatus. It has also been found that the point of a wave at which the circuit through relay 5 is closed greatly affects the operating characteristics of this relay, i. e., if for example, the circuit is closed at the zero point of
40 the wave, the relay will operate at a much higher resistance in this circuit than if it is closed at the peak of a wave. It therefore follows that should the ringing relay not be accurately adjusted, it might not operate if the circuit through its winding was closed at the peak of a wave but function properly if the circuit was closed at any other point of the wave. As an illustration of the close
45 limits ordinarily required in telephone systems of this type it might be mentioned that the ringing relay may be required to operate with a resistance of 450 ohms and not operate with a resistance of 850 ohms in the circuit. Considering therefore that the

worst operating conditions are encountered at the peak of a wave, the test circuit as arranged in accordance with this invention has been designed so that when a relay is under test, it is not subjected to the test until the current from the ringing source has reached the peak of a wave and a detailed description of an arrangement on this basis will now be described.

The test circuit is preferably arranged so that the apparatus, except the battery supply, is contained in a test box the outline of which is indicated by a dotted line 20. This box may include keys 21, 22, 23 and 24, relays 25, 26, 27 and 28, signal lamp 29 and jacks 30 and 31. In performing a test a special cord 32 is used, the conductors of which are provided with contact points or clips 33, 34 and 35 which may be connected to the conductors leading to the winding, and armature and back contact of relay 5, while plug 36 of this cord is inserted in jack 30 and battery and ground are supplied to the testing circuit from plug 38 which is inserted in jack 31.

If relay 5 is to be tested for operation at the peak of a wave under conditions simulating the actual line conditions when the receiver is removed from the hook, keys 21, 23 are operated and the following functions take place. Line circuit is closed from battery, tip contacts of plug 38 and jack 31, one branch extending through resistance 40, right hand winding of relay 25, inner right hand armature and back contact of relay 28, make-before-break contacts of relay 27, upper closed contacts of key 21 to ground at the sleeve contacts of jack 31 and plug 38, while a second branch extends from battery at plug 38 and jack 31, through resistance 41, lamp 29, make-before-break contacts of relay 27 to ground at plug 38. The first circuit causes the operation of relay 25, whereas the second circuit causes lamp 29 to be dimly lighted due to resistance 41. The operation of relay 25 closes a circuit from battery at plug 38 through resistance 43, right-hand winding of relay 26, right-hand armature and front contact of relay 25 to ground at plug 38. This causes the operation of relay 26 which in turn closes a circuit for the operation of relay 27 as follows: battery at plug 38, sleeve contacts of jack 30 and plug 36, contact 35, armature and back contact of relay 5, contact 34, ring contacts of plug 36 and jack 30, winding of relay 27, right-hand armatures and front contacts of relays 26 and 25 and inner right hand armature and back contact of relay 28 to ground at plug 38 as previously traced. Relay 27 in operating, closes a circuit for relay 28 as follows: battery at plug 38, left-hand armature and front contact of relay 27, winding of relay 28, upper closed contact of key 21 to ground at plug 38. Relay 27 also breaks the circuit

for lamp 29 through resistance 41 at its make-before-break contact and provides a locking circuit for itself at its right-hand armature and front contact to ground at plug 38. The operation of relay 28 closes a locking circuit for itself through the inner-left-hand armature and front contact which is independent of the original energizing circuit through the left-hand armature and front contact of relay 27. Relay 28, in operating, also breaks the original energizing circuit through its inner right-hand armature and front contact for relays 25, 26 and 27. Relays 25 and 26, however, are held up through the right-hand armature and front contact of relay 27, while relay 27 is held up as previously described. As stated relay 27 by breaking its make-before-break contacts opens the energizing circuit for lamp 29 which is thereby extinguished to indicate that relays 25, 26, 27 and 28 have functioned properly. Relay 28 now closes a circuit through its outer-left hand armature and front contact for ringing trip relay 5 as follows: ringing source 11, winding of relay 5, contact 33, tip contacts of plug 36 and jack 30, outer left-hand armature and front contact of relay 28, left hand armature and front contact of relay 25, winding of relay 25, resistance 44 to ground at plug 38, but as the values of the resistance of the left-hand winding of relay 25 and resistance 40 are such as to prevent relay 5 from receiving sufficient current from alternating current source 11, this relay will not operate at this time. Current from the alternating current source 11 through the left-hand winding of relay 25 may, however, be of such direction that it will oppose the direct current through the right-hand winding of relay 25 to cause it to release, i. e., if relay 28 operated when a negative wave is produced from the alternating current source 11, nothing will happen, but if a positive wave is passing at this time, relay 25 will be released. Upon the release of relay 25, on a positive wave, current from source 11 will now be connected through the left-hand armature and back contact of relay 25, left hand armature and front contact of relay 26, left-hand winding of relay 26, resistance 44 to ground at plug 38, and relay 26 will then presently be released, i. e., as soon as the next negative current is produced and has its peak, as it is then in proper direction and strength to oppose the direct current in the right-hand winding and cause the release of relay 26. Therefore, as soon as relay 26 is released, this negative current wave which is now at its peak is switched at the left-hand armature and back contact of relay 26 through the closed contacts of key 23, resistance 45, middle closed contacts of key 21 to ground at plug 38. Resistance 45 is of such value that is simulates the actual line conditions when the receiver is off the switchhook and the current from the alternating current source 11 through relay 5, which as stated is at the peak of its negative wave, causes relay 5 to operate, provided of course this relay is properly adjusted for this value. Relay 5 in operating, opens at its armature and back contact the circuit for relay 27 and this relay in releasing closes at its make-before-break contacts the following circuit: battery at plug 38, outer right-hand armature and front contact of relay 28, lamp 29, make-before-break contacts of relay 27, to ground at plug 38. Lamp 29 is now, brightly illuminated as resistance 41 has been removed from the energizing circuit therefor and this illumination of lamp 29 serves as an indication that relay 5 has operated under the worst conditions encountered in practice, that is, at the peak of a wave from the varying source 11 and at the proper line conditions. The test for the operation of relay 5 is now completed and key 21 may be released, causing relays 28 and 5 to return to normal.

If relay 5 is to be tested for a non-operate condition, keys 22 and 23 are actuated and the functions of relays 25, 26, 27 and 28 and lamp 29 are the same as previously described, up to the point where relay 28 has operated, when a circuit is in this case completed for relay 5 as follows: alternating current source 11, winding of relay 5, contact 33, tip contacts of plug 36 and jack 30, outer left-hand armature and front contact of relay 28, left-hand armatures and back contacts of relays 25 and 26 in series through the closed contacts of key 23, resistances 45 and 46 in series, the middle closed contacts of key 22, resistance 47, to ground at plug 38. This circuit which now includes resistances 46 and 47 in addition to resistance 45, simulates the actual conditions encountered in practice for the non-operation of the ringing relay 5. It should be noted that in this instance if relay 5 is properly adjusted, it will not operate and consequently relay 27 will remain operated thus the circuit for lighting lamp 29 is not completed. In this case, therefore, the non-operating condition of relay 5 is indicated by the non-operation of lamp 29. If relay 5 is not properly adjusted but would operate in this latter case, relay 27 will release and lamp 29 will be brightly illuminated to indicate this condition.

Now, in order to adjust relay 5 to function properly under these test conditions, key 24 is operated in conjunction with either key 21 or key 22, thus changing the resistance conditions by including a resistance 48 in series with the resistance 45 for the operating circuit or including the resistance 48 and eliminating the resistance 46 for the non-operating circuit for relay 5.

and the contacts of relay 5 may now be manually adjusted so that relay 5 operates or does not operate depending upon which one of the keys 21 or 22 is actuated. If relay 5 now operates or does not operate with these resistance values in the circuit, it is assumed that it will function under the worst conditions encountered in practice, that is, operate with a resistance of the value of 10 resistance 45 or not operate with a resistance of the combined values of resistances 48, 46 and 47. In other words, the adjustment is such that a slightly more severe condition than is encountered in practice has to be 15 met by this relay.

It is considered that a detailed description of the operation of the automatic circuit shown in Fig. 2 is not necessary, as it forms 20 no part of this invention, except to say that the ringing trip relay 50 thereof may be tested and adjusted in exactly the same manner as was relay 5 by connecting contacts 33, 34 and 35 to the winding, armature and back contact of relay 50. It should be assumed 25 that the sequence switch well known in the art and shown in this figure, should be stopped at a position where the springs thereat will not make connections that will interfere with the proper testing of relay 50 and if necessary these springs may be blocked by 30 inserting insulating strips between the contacts and the springs.

It should be understood that the invention as disclosed and applied to the systems 25 described above is not confined to these particular arrangements but may well be applied to systems in which other types of ringing current sources are employed, for example, a direct current source may be used; that is, 30 the relays may be adjusted to operate in a circuit supply comprising a shunt current on which an attenuating current has been superimposed. Nor should the invention be considered as confined to the particular use 35 shown but may well include other uses such as for example, the circuits may be arranged so that the circuit through the ringing relay is closed at any desired point of a wave by phase shift of the control circuits or by use 40 of time counting devices as is well known in the art. These circuits and relay combinations may also readily be employed to 45 count off a number of half cycles of the supply current or in fact any use involving 50 the control or test of relay as may be desired in the modern telephone practice that require the application of the principles underlying the invention as herein disclosed.

What is claimed is:

60 1. A method of testing relays consisting in subjecting a relay to testing current from an alternating current source at the peak of a wave and indicating the result of the test.

65 2. A method of testing relays consisting

in subjecting a relay to a testing current of a value to cause its operation from an alternating current source at the peak of a wave if said relay is properly adjusted, subjecting 70 said relay to testing current of a value that will not cause its operation from an alternating current source at the peak of a wave if said relay is properly adjusted.

3. A method of testing relays consisting in subjecting a relay to a testing current of 75 a value to cause its operation from an alternating current source at the peak of a wave if said relay is properly adjusted, subjecting said relay to testing current of a value that will not cause its operation from an alter- 80 nating current source at the peak of a wave if said relay is properly adjusted and indicating the results of said tests.

4. A method of adjusting relays consisting in subjecting a relay to a current of a 85 certain value from an alternating current source at the peak of a wave, adjusting the relay to respond thereto, subjecting said relay to a current of a certain other value from the alternating current source at the 90 peak of a wave and adjusting the relay so as not to respond thereto.

5. A method of testing and adjusting the electro-responsive characteristics of relays consisting in subjecting a relay to a testing 95 current of a certain value from an alternating current source at the peak of a wave to cause it to respond if properly adjusted, subjecting said relay to a testing current of a certain other value from an alternating current source at the peak of a wave to which it will not respond if properly adjusted, subjecting said relay to an adjusting current of a certain other value from an alternating current source at the peak of a wave, adjusting 100 said relay to respond to said adjusting current, subjecting said relay to an adjusting current of a second value from an alternating current source at the peak of a wave and adjusting said relay so as not to respond 105 to said second mentioned adjusting current, the first mentioned adjusting current being of a slightly higher value than the first mentioned testing current and the second mentioned adjusting current being of a slightly 110 lower value than the second mentioned testing current.

6. In a system for testing the electro-responsive characteristics of relays the combination of an alternating current source and 115 means for applying current from said source at the peak of a wave to a relay.

7. In a system for testing the electro-responsive characteristics of relays the combination of an alternating current source and 120 means for applying current from said source at the peak of a wave to a relay and a signaling means for indicating the response of said relay.

8. In a system for testing the electro-re- 125

sponsive characteristics of relays the combination of means for subjecting a relay to be tested to currents from said source at the peak of a wave and means for regulating the 5 values of said currents so that said relay if properly adjusted will operate or not operate according to the limits set by the values of the current applied.

9. In a system for testing the electro-re- 10 sponsive characteristics of relays the combi- nation of an alternating current source and means for subjecting a relay to be tested to currents from said source at the peak of a wave, means for adjusting the value of the 15 testing current so that if said relay is prop- erly adjusted this current will cause it to respond and means for adjusting the value of the testing current so that if the relay is properly adjusted the current will not cause 20 it to respond.

10. In a system for testing the electro-re- 25 sponsive characteristics of a relay the com- bination of an alternating current source, means for subjecting a relay to be tested to current from said source at the peak of a wave, means for adjusting the value of the testing current so that if said relay is prop- erly adjusted this current will cause it to respond, means for adjusting the value of 30 the testing current so that if the relay is properly adjusted it will not respond to said current and signaling means for indicating the response or nonresponse of the relay

when subjected to tests with the current ad- justed to either of said values. 85

11. In a testing system a testing unit com- 40 prising means for testing the electro-respon- sive characteristics of relays and signaling means to indicate testing conditions, a relay to be tested, a source of alternating current 45 associated with said relay and a cord for connecting said testing unit with said relay so that the alternating current source will serve as a source of testing current and so that the contacts of said relay may be in- cluded in the control of said signaling means.

12. In a system for testing the electro-re- 50 sponsive characteristics of relays the com- bination of an alternating current source, means for subjecting a relay to be tested to a current from said source at the peak of a wave, means for regulating the values of 55 said current so that said relay if properly adjusted will operate or not operate accord- ing to the limits set by the values of the current applied and means for regulating the values of said current to certain other limits so that the relay may be adjusted to operate or not operate in accordance with said 60 second setting of the values of the currents applied.

In witness whereof, I hereunto subscribe my name this 6 day of September A. D., 1924.

LELAND J. STACY.
